UNITED STATES PATENT OFFICE.

WILLIAM J. DIXON, OF KANSAS CITY, MISSOURI.

CAR-REPLACER.

1,082,936.

Specification of Letters Patent.

Patented Dec. 30, 1913.

Application filed October 30, 1911. Serial No. 657,550.

To all whom it may concern:

Be it known that I, WILLIAM J. DIXON, a citizen of the United States, residing at Kansas City, in the county of Jackson and 5 State of Missouri, have invented certain new and useful Improvements in Car-Replacers, of which the following is a specification.

This invention relates to car replacers, and has for its object to produce a device 10 of this character by which, used in duplicate, the operation of replacing a railway car upon the tracks may be easily and quickly performed, and which may be used on either the right or left hand rail and without regard to the direction in which the derailed car is to be moved.

With this and other objects in view, the invention consists in certain novel and peculiar features of construction and organization as hereinafter described and claimed; 20 and in order that it may be fully understood reference is to be had to the accompanying drawing, in which:—

Figure 1, is a top plan view of a section 25 of railway track temporarily equipped with a pair of replacers embodying my invention. Fig. 2, is an enlarged section on the line II—II of Fig. 1. Fig. 3, is a section on the line III—III of Fig. 1.

30 In the said drawing, the main body of the car replacer 1 is in the form of a block, which, in side view tapers downwardly and rearwardly and in plan view tapers forwardly. In the vertical plane of its longitudinal center the replacer has a longitudinal bifurcation 2, extending from a point about midway its length to its rear extremity, and from the front end of the bifurcation and forming a continuation thereof, it 35 is provided in its under side with a channel 3 of sufficient size to snugly receive a track rail of the largest size. The replacer is adapted to be placed over a rail, so that the latter shall extend through the bifurcation and channel as shown, and to aid in preventing it slipping or creeping on the rail in a forward direction as a car is being pulled upon it, it is provided at opposite sides of its bifurcation and channel, with de-

pending teeth or spurs 4, some or all of 50 which, are adapted for embedment in the ties upon which the replacer is adapted to rest.

The replacer is provided at its side margins with upwardly projecting and forwardly converging and preferably inwardly bowed flanges 5, rising to a height at their inner edges about equal to the depth of the flanges of a car wheel. Near the front end of the replacer the said flanges are provided with upward extensions or flanges 6, which at 7 form cams which converge forwardly at greater angles than the inner sides of the flanges 5, and said extensions near the front extremity of the replacer, are 65 formed with short forwardly diverging walls or faces 8. Between the walls or faces 8, a substantially triangular guide lug 9 projects upward from the upper or inclined face of the replacer so as to divide the space 70 between flanges 5 into a pair of forwardly diverging channels 10, each extending in the same general direction as the cam 7 at the opposite side of the guide lug, and so spaced from such cam that when the outer face 75 of a car wheel bears against one of the cams 7, the flange of said car wheel shall be guided so as to pass into the channel 10 at the opposite side of the guide lug.

Along the margins of the bifurcation of 80 the replacer are upwardly projecting ribs 11 of preferably less height than the depth of a wheel flange, and near their rear ends said ribs 11 are formed with upwardly projecting perforated ears 12, with one of which 85 a link of a chain 13 is pivotally connected, said chain being provided with a hook 14 at its opposite end, for engagement with the other perforated ear. At its front end and at opposite sides of channel 13, the replacer 90 is preferably provided with recesses 15, within which are loosely pivoted gravity dogs 16, and the lower ends of the dogs extend at such angles to the length of the dogs that when said ends rest upon the bottoms of recesses 15, the dogs extend convergingly upward as shown in Fig. 3. The dogs are cut away at their upper inner corners to pro-

vide supplemental shoulders 17 for a purpose which hereinafter appears.

The side lug is provided in its upper front end with an arcuate recess 18, and engaging 5 said recess with a hinge relation is the hook terminal 20 of a wheel-lowering toe-piece 19, the body of the toe-piece being of substantially triangular form in side view with its hypotenuse side sloping downwardly and 10 forwardly in order that the wheel when properly alined with the track by the replacer, will roll downward on said toe-piece instead of dropping or falling from the side lug directly onto the rail, as under the 15 weight of a heavy object, such as a locomotive or a car, said dropping is attended with considerable danger of injury to the wheels.

In practice there will be two replacers used, each being fitted as shown, upon one 20 of the rails 21 of a car track and upon at least two of the cross ties 22 of said track, so that some of the spurs 4 shall be embedded 25 in the underlying ties without regard to whether the same are equally spaced or not.

When the replacers are thus arranged the chains are passed under the rails and the 30 hooks 14 are engaged with the lugs 12 at the opposite sides of the rails from the lugs to which the chains are permanently attached, thus utilizing the rails to prevent upward movement of the rear ends of the replacers when the weight of the car is on the front ends thereof. The chains also serve by bearing against the adjacent ties, to prevent 35 forward creeping of the replacers.

As the replacers are placed in the positions explained, the rails, as they enter the channels 3, force the dogs 16 outwardly and then permit them to swing back under the balls 40 of the rails, it being understood that if the rails are low rails, the shoulders 17 engage the lower corners of the balls of the rails, so that in either event the weight of the car imposed on the rear ends of the replacers 45 cannot tilt the front ends of the same upwardly.

Assuming that a car is off the track with its wheels upon the cross ties and that the replacers have been secured upon the track at 50 the desired distance ahead of the displaced wheels, the engine is started forward so as to cause the displaced wheels to ride upward on the upper or inclined faces of the replacers, one of the wheels climbing the replacer 55 outward of the bifurcation of the latter and the other climbing the other replacer inward of the bifurcation of the same. As the wheels continue to ascend, the tread portion of the one outward of the adjacent track 60 rail, will overlie and partly rest on flange 5 and be caused by such wall to gradually approach the vertical planes of the rails. When the wheels have progressed a certain distance, the outer side of the one first-re-

ferred to will come in contact with the adjacent cam 7, which will then force both wheels in such direction that eventually they will stand directly over the longitudinal centers of the replacers just rearward of the guide lugs, at which time the flanges of the wheels 70 will be at the inner sides of the guide lugs, it being noticed in this connection, that the extension 6 at the outer side of the flange 5, of the right-hand replacer, guards against the wheels being pushed too far by the said 75 engaged cam. The forward movement continuing, the tread portions of the wheels ride upon the guide lugs 9, and then pass over the hinge terminals of toe-pieces 19, and roll downward over the latter and are deposited 80 without material shock or jar upon the rails, it being noticed in this connection that the toe-pieces 19 are so connected that they can swing downwardly to a lower position than they occupy in Fig. 2, for the purpose of 85 resting upon shallower or lower rails.

To guard against any possibility or danger of a wheel dropping into the bifurcation 2 of a replacer and wedging between the rail 90 therein and the adjacent wall of such bifurcation, and thereby perhaps breaking the replacer, I have provided the ribs 11, which act as abutments to deflect the wheels into parallel relation with the track rails.

From the above description it will be apparent that I have produced a car replacer embodying the features of advantage enumerated as desirable and I wish it to be understood that while I have illustrated and described the preferred embodiment of the 10 same I reserve the right to make all changes properly falling within the spirit and scope of the appended claims.

I claim:

1. A car-replacing block provided with 1 means for securing the same to a track, said block being provided with guiding flanges upon its top surface, said flanges extending along the sides of the block and widening and converging from one end of the block to 1 the other, a second pair of guiding flanges mounted one on each of the first flanges at the widened portions thereof, and converging at a greater angle than and toward the same end of the block as the first flanges, and 1 a triangular lug located between the first flanges at their widened ends.

2. A car replacer, comprising a block of triangular form, provided with converging side walls projecting upwardly above the top 1 face of the block and with a triangular lug projecting upwardly from said face between the said walls where the space between them is narrowest, and a toe-piece pivotally connected to said lug and adapted to swing into 1 different vertical positions with relation to the adjacent end of the block to accommodate different heights of rails.

3. In a car replacer, a block provided with a longitudinal channel in its underside to receive a rail, and with recesses in its front end opening into said channel at opposite sides thereof, and upwardly-converging gravity dogs in said recesses, pivoted at their lower ends to the block and provided at their inner edges below their upper extremities, with upwardly-facing shoulders, and capable of

swinging outwardly to permit the head of a rail to be passed up between them.

In testimony whereof I affix my signature, in the presence of two witnesses.

WILLIAM J. DIXON.
